PEDAL DRIVEN TOY VEHICLE

Robert L. Hanna, 1326 N. Manhattan Ave.,
Manhattan, Kans.

Filed May 14, 1962, Ser. No. 70,106

Term of patent 14 years

(Cl. D34—15)

FIGURE 1 is a side elevation of a pedal driven toy vehicle showing my new design, the opposite side being substantially the same.

FIGURE 2 is a top plan view of the toy of FIGURE 1.
FIGURE 3 is a bottom plan view of the toy of FIGURES 1 and 2.

The dominant features of the design are shown in solid lines.

I claim:

The ornamental design for a pedal driven toy vehicle, substantially as shown and described.
